MATCH PACKET

Rodney S. Pullen, Akron, Ohio, assignor to Pul-
lenite Company, Philadelphia, Pa., a corpora-
tion of Pennsylvania

Application October 19, 1931. Serial No. 569,631

6 Claims. (Cl. 206—29)

My invention relates to match packets in which the matches are ignited during their longitudinal withdrawal from the packet, stick-end foremost and the matches in the packet threading spaced rows of perforations of a wrap, the invention being more particularly directed to the wrap of a match packet of the character indicated.

In this type of match packet a short flap adjacent one row of perforations folds down against the exposed match portions intermediate the threaded rows and a long flap adjacent the other row of perforations folds down over the short flap, thence around the projecting match heads and up against the portion of the wrap intermediate the perforations with the wrap fastened in folded position.

The perforations of the row adjacent the short flap are desirably star cuts, the petticoats thereof separating or spreading by the insertion of the matches which are entered stick-end foremost. The row of perforations adjacent the long flap are normally round holes, and the present invention is directed to a modifying improvement of the wrap at a portion thereof near this row of perforations adjacent the long flap. For the purpose of more easy identification I herein call the perforations adjacent the long flap the stick end or forward perforations of the wrap and the perforations adjacent the short flap the head end or rearward perforations of the wrap.

It will be understood that in the finished packets the wrap inner folds present strips of ignition material on both sides of the matches and adjacent the normally round-cut holes, a match igniting as its head passes between these strips immediately before reaching the round hole perforation.

The star perforations through which the heads must first pass are intended to offer considerable resistance to the withdrawal movement of the match in order that a user may involuntarily pull out the match with considerable velocity, but I find resistance at the round holes is undesirable.

It has sometimes happened that a user has failed to fully withdraw a match at a first attempt, letting the fingers slip from the match shank when the match head engages the wrap at the round-cut perforation.

When this has happened, the match head having passed through the strips of ignition mate-

rial has been already ignited before the fingers of the user have slipped from the match shank and the ignition has resulted in a burning up of the ignition material of adjacent matches and possibly even in an igniting of the whole packet 55 of the matches although this has been unusual.

This condition is partially incident to the fact that match heads vary considerably in size, so that round-cut holes that readily pass match heads of average size offer an abnormally high 60 resistance to the passage of heads of abnormally large size.

A purpose of the present invention is to eliminate or greatly reduce the resistance offered to the match head by reason of the round cut hole 65 through which the match must pass during withdrawal.

A further purpose is to weaken a portion of the wrap longitudinally of the matches and of the wrap adjacent the stick end holes, preferably 70 upon the side thereof that in the finished packet is adjacent the turned up portion of the long flap and optionally upon the other side thereof or/and upon both sides thereof.

A further purpose is to avoid or reduce the 75 stresses upon the wrap at points intermediate the holes of the row of holes toward the stick end of the packet.

A further purpose is to slit or score the wrap 80 for a short distance from the individual stick end perforations and in a direction longitudinal of the wrap adapting the portions of the wrap rearwardly adjacent the holes to yield to accommodate strains upon the wrap portions intermediate the holes.

A further purpose is to avoid any danger of 85 local ruptures between successive holes of a row by means of local ruptures extending from the holes in a direction transverse to the row.

A further purpose is to secure an adaptation 90 to easy rupture from individual holes of the wrap in a direction transverse to the row and by the threading of matches through the holes and without materially lessening an adaptation of the wrap to resist a transverse elongating of the 95 holes when folding the wrap to its match receiving position.

Further purposes will appear in the specification and in the claims.

I have elected to show one main form only of 100

my invention, showing however a few only of the modifications thereof with respect to a detail.

Figure 1 is a perspective view of a match packet embodying a desirable form of my invention.

Figure 2 is a view of the packet of Figure 1 turned reversely as compared to the position of Figure 1 and having a wrap portion broken away at the rear of the packet.

Figure 3 is a rear elevation of the wrap of Figures 1 and 2 with the long flap broken away to disclose the stick end connections between the matches and wrap.

Figure 4 is a vertical section of the structure of Figure 3 taken upon the line 4—4 thereof.

Figure 5 is a view corresponding to Figure 4 except that the forward match in Figure 4 has been withdrawn disclosing the next match and the head end and stick end wrap perforations from which the first match has been withdrawn.

Figure 6 is a top plan view of a wrap unfolded.

Figure 7 is a view corresponding generally to Figure 6 but illustrating that the wrap may be weakened upon both sides of the stick end row of perforations and also illustrating that the character of weakening may be widely varied.

Figure 8 is a view corresponding generally to Figure 3 except that the wrap has been fastened in folded position in a different way from that used in the structure of Figure 3.

Figure 9 is a rear perspective view, having a wrap partly broken away at the rear of the structure shown in Figure 8.

Like numerals refer to like parts in all figures.

Describing in illustration and not in limitation and referring to the drawing:—

Typical wrap blanks of a match packet of the type to which the present invention is directed are intended to be illustrated in Figures 6 and 7, these figures including however in slightly different forms added features that embody the present invention.

The Figures 6 and 7 show wrap blanks, herein called cards or wraps, that are alike except with respect to the features relating to the present invention, and in both views the inside faces of the blanks or cards are presented toward the beholder. Each card is assembled with matches and one or more metal fasteners to form a finished packet.

The outside, or in the figures the under face of the card, is scored at the lines 10, 11, 12, 13, 14, and 15, and the inside or upper face is coated with ignition material over the areas 16 and 17 and the card is provided with a transverse row of petticoated holes 18 between the score lines 14 and 15 and a second transverse row of holes 19 between the score lines 12 and 13, the latter holes being preferably clean-cut and round.

The petticoats of successive petticoated holes 18 are preferably relatively staggered in order to increase the distance between the radial cuts of one hole and the corresponding cuts of the adjacent holes and to thereby avoid weakening the card along the row of petticoated holes.

The present invention is directed to the provision of means for avoiding danger of incipient tearings of the wrap at the individual clean-cut holes 19 during the insertion of the matches and between the holes in a direction along the row. Such incipient tearings occasionally occur in assembling the packets of the prior art and with a very undesirable weakening of the wrap at portions thereof along the row of clean-cut holes 19.

I accomplish the desired result by weakening the wrap adjacent the holes laterally of the row

of holes as at each hole 19 laterally of the row toward the short flap end of the wrap or/and laterally of the row toward the long flap end of the wrap.

In Figure 6 this weakening has been accomplished by short score lines 20 cut approximately normal to the alinement of the row and approximately tangentially from each hole toward the short flap portion 21 of the wrap.

When assembling the wrap and matches into a packet the blank is folded up along the lines 13 and 14 so that the holes of both rows are vertical and matches 22, stick-end forward, are then threaded first through the petticoated holes 18 and then through the clean-cut holes 19, the match heads usually seating in the inwardly deflected petticoats as seen at 18', Figures 4 and 5.

The short flap 21 is then folded down along the score line 15 upon the inserted matches and the long flap 23 is then folded down over the short flap, down around the projecting match heads and up against the portion of the wrap intermediate the perforations, the wrap being fastened in folded position in any suitable way, as by staples 24, Figures 1 to 3, or a bale 25, Figures 8 and 9.

It has been found that match packets of this type of the prior art sometimes tear during the insertion of the matches at the round holes in a direction from hole to hole, the result having been a weakening of the wrap along the row of the round holes 19 and in consequence there have been occasional failures of match ignition during withdrawal, doubtless by reason of the lessened pressure between the head of the match during the withdrawal and the ignition surfaces 16 and 17 between which the match head passes through the match withdrawal.

I have discovered that danger of tearing the wrap at points between the holes during the insertion of the matches may be avoided by weakening the wrap adjacent the holes laterally of the row, on one or other or both sides thereof away from the row so that any incipient tearings take place transversely of the row instead of perhaps along the row.

While obviously different ways may be used for securing the weakening of the wrap at the holes laterally of the row of holes and while I have found that any one of the several different weakening methods may be preferable to any of the others under suitably different special circumstances, that it may sometimes be more desirable to weaken at the holes at both sides of the row, yet I have more usually preferred to secure the weakening on one side only of the row, the side toward the short flap end of the wrap, and to secure the weakening by strongly scoring for short distances from the holes away from the row.

When the weakening is on the side of the row toward the short flap end of the wrap any incipient tearings incident to this weakening is hidden by the end portion 26 of the long flap in the finished packet, the finished packet presenting from the front an appearance of clean-cut holes as illustrated at 27 in Figures 1, 4 and 5 while directly back of the individual matches and between the extended match sticks and the outer portion 26 of the long flap the wrap may be incipiently torn or ruptured at 28 to project outwardly or upwardly back of the matches somewhat as indicated at 29, these outward projections at 29 being substantially hidden by the matches and therefore not affecting the good appearance of the finished packet.

I have found it usually preferable to weaken

the wrap at the holes laterally of the row by the short slits or score lines 20 from the holes 19, making the slits or scorings 20 nearly through the wrap but not quite through the wrap and usually have preferred to make these heavy score lines extend tangentially away from the holes and approximately parallel to the wrap sides.

Two slits or score lines from near opposite sides of each of the holes appear to be better than single slits from the middles of the respective holes.

Except for the desirability of hiding in the finished packet any incipient tearings of the wrap at the holes 19, the slits or score lines 20 may be upon both sides of the row.

These slits or score lines thus may or may not extend tangentially from the holes; may or may not extend parallel to the length of the wraps; and may or may not go all the way through the paper.

If the slits or scorings from the individual holes flare away from the holes as indicated in Figure 7 they preferably should not be cut through the paper, in that flaring the slits away from one another at the individual holes as indicated in Figure 7 may bring the slits of adjacent holes so near together as to unduly weaken the wrap if the slits go clear through the wrap. For this reason it may often be more desirable to make the slits flare toward the holes rather than away from the holes, and even then it may be better not to slit all the way through the wrap.

I have found that slitting or scoring away from the holes transversely to the row is much better than elongating the holes transversely to the hole.

When the holes are elongated transversely to the length of the row, the wrap has a tendency to draw together during the assembly, particularly when the long flap is turned upright.

The result may then be loss in proper registry with the incoming matches and a greater tendency for tearing the portions of the wrap in the row and between the holes.

The slits or score lines 20 do not materially weaken the strength of the wrap against compression stresses in a direction tending to narrow the width of the wrap at the row, and as a consequence the slitting or scoring makes no material change in the registry of the holes, such as tends to occur if the holes are elongated laterally of the row rather than merely weakened laterally of the row, as by slitting from the individual holes and away from the row.

Obviously the wrap may be fastened in its folded position in any suitable way. In Figures 1, 2 and 3 this fastening has been shown as comprising staples 24 which are outside of and parallel to the end matches of the packet and go all the way through the packet.

In Figures 8 and 9 the fastening is illustrated as a long bale or staple 25 transverse to the matches. This bale has a body portion 30 that extends across the short flap 21 that fronts the matches the long flap, the staple being inserted before turning down the long flap which is turned down on to the staple body 30 and the underlying short flap and thence down around the match heads and up against the other side of the packet as already described.

The tines 31 of the bale pass through the long flap, suitably through slits 32 thereof, as the long flap is being folded around to its final position, after which the tines are preferably bent outwardly around the edges of the packet to clinch on the outside of the short flap and under the long flap as indicated at 33, the folded or clinched ends of

the tines being thus closely adjacent the body of the staple.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

1. A wrap for a match packet of the character indicated and having spaced transverse rows of holes and portions along one side of one of the rows laterally adjacent the holes weakened and the said wrap having strips of ignition material one strip adjacent the short flap end of the wrap and the other strip overlapping the said weakened portions along the said one row.

2. A wrap for a match packet having a packet wall transverse to the match length located near the stick ends of the matches and having a row of clear holes in it to pass the match sticks, the walls to the side of the row of holes being weakened to permit lateral breaking out and the walls between the holes of the row having full strength.

3. A wrap for a match packet of the type which lights the matches during withdrawal from the packet having a first transverse row of spaced holes whose walls are adapted to engage the matches near their head ends and retard the matches during withdrawal from the packet and having a second transverse row of spaced holes at a distance from the first row longitudinally of the wrap, adapted to pass the matches near their stick ends and having walls free from retarding engagement with the match sticks and weakened to relieve the pull required by the user after the match has been struck and before the match head has been withdrawn from the packet.

4. A wrap for a match packet of the type which lights the matches during withdrawal from the packet having a first transverse row of spaced holes whose walls are adapted to engage the matches near their head ends and retard the matches during withdrawal from the packet and having a second transverse row of spaced holes at a distance from the first row longitudinally of the wrap, adapted to pass the matches near their stick ends and having walls free from retarding engagement with the match sticks, weakened in a direction longitudinal of the wrap to relieve the pull of the user after the match has been struck and before the match head has been withdrawn from the packet and having unweakened walls between each hole and the next hole on either side in the row of holes.

5. A match packet comprising a wrap folded upon itself to form a match-head compartment, a match-striking compartment, a partition wall between the match-head and match-striking compartments, a wall at the stick-end of the match-striking compartment and side walls of the packet, a row of matches having their heads in the match-head compartment and their stick ends extending through openings in the partition wall between the match-head compartment and the match-striking compartment, the walls of which partition wall openings engage and retard the matches, and passing through openings in the wall at the stick-end of the match-striking compartment, the edges of the stick-end wall

openings being free from retarding engagement with the match sticks and being weakened to relieve the pressure upon the matches after the match heads have been ignited and before they have been withdrawn from the packet, and match-striking material on an inner wall of the match-striking compartment, adapted to strike the matches during withdrawal.

6. A match packet comprising a wrap folded upon itself to form a match-head compartment, a match-striking compartment, a partition wall between the match-head and match-striking compartments, a wall at the stick-end of the match-striking compartment and side walls of the packet, a row of matches having their heads in the match-head compartment and their stick

ends extending through the match-striking compartment passing through openings in the partition wall between the match-head compartment and the match-striking compartment, the walls of which partition wall openings engage and retard the matches, and passing through openings in the wall at the stick-end of the match-striking compartment, the edges of the stick-end wall openings being free from retarding engagement with the match sticks and being weakened in a direction transversely of the row of matches and unweakened between adjoining matches, and match-striking material on an inner wall of the match-striking compartment, adapted to strike the matches during withdrawal.
